(57) **CLAIM**

The ornamental design for a tablet dock, as shown and described.

DESCRIPTION

FIG. 1 is a perspective view of the tablet dock;

FIG. 2 is a front view of the tablet dock;

FIG. 3 is a back view of the tablet dock;

FIGS. 4 and 5 show alternate side views of the tablet dock; and,

FIGS. 6 and 7 show front and back views of the tablet dock. Broken lines shown in the drawings illustrate portions of the tablet dock and form no part of the claimed design.
